(57) CLAIM

The ornamental design for an escalator balustrade transition section, as shown and described.

DESCRIPTION

FIG. 7 is a right side elevation view of the first embodiment escalator of FIG. 1 and the second embodiment escalator of FIG. 4 showing my new design, the left side elevation view being a mirror image.

The broken lines in the figures show portions of the escalator balustrade transition section, which form no part of the claimed design. The dash-dot broken lines in the figures shown boundaries, and form no part of the claimed design.
